LIQUID VOLUMETRIC MEASURING SYSTEM
Roy Shepherd, Tulsa, Okla., Henry F. McCabe, Fort Worth, Tex., and Jack E. Fogarty, Tulsa, Okla., assignors, by mesne assignments, to Union Tank Car Company, Chicago, Ill., a corporation of New Jersey
Filed Nov. 29, 1956, Ser. No. 625,186
6 Claims. (Cl. 137—122)

The invention involves a novel production system for oil wells and particularly relates to an arrangement for measuring the productivity.

As is well known to those familiar with the petroleum industry, one of the major current problems relates to the conservation of product and particularly to the elimination of product loss due to vaporization. This problem faces the industry in all phases of petroleum refining, including initial production of the crude from the well.

Additionally, it will be appreciated that the quantity of production of raw usable crude from a well must be accurately determined for many reasons, such as for example, royalty payment. With this in mind, it will be understood that accuracy in measuring usable crude is of extreme importance as well as the prevention of loss of production through vaporization.

Several disadvantages have appeared in the systems currently in use for measuring usable crude well production. Among these disadvantages is that the systems currently employed are of such a nature that they tend to accommodate a rather high percentage of product loss through vaporization. Additionally, many of these systems have field difficulties in that production is sometimes lost through failure of the relatively complex pipe and valve arrangements and the like. Further, the corrosive effects of the product vapors and the like have unfavorably attacked the equipment in use.

With this in mind, it is a general object of the invention to provide an improved arrangement which avoids many of the problems facing industry today.

It is a specific object of the invention to provide an arrangement of the type described which reduces product loss through vaporization, and, by relatively simple conduit arrangements tend to eliminate product loss through faulty piping and valving.

It is a further object of the invention to provide an automatic arrangement which reduces the manual operations required in arrangements of this type and which provides semi-automatic switching in a series arranged tank battery.

These and other objects of the invention will become apparent in the course of the following description and from an examination of the concerned drawings, wherein:

FIGURE 1 is a schematic view of an arrangement of the type described.

FIGURE 2 is a partially fragmentary side elevational view of a pair of measuring tanks in the system described.

FIGURE 3 is a partially fragmentary top view of the structure shown in FIGURE 2.

FIGURE 4 is a fragmentary sectional view taken along line 4—4 of FIGURE 3.

FIGURE 4A is a fragmentary, partially sectional view taken approximately along line 4A—4A of FIGURE 2, and

FIGURE 5 is a fragmentary sectional view taken along line 5—5 of FIGURE 3.

Describing the invention in detail and directing attention to FIGURE 1, it will be understood that a producing head is indicated generally at 2, said well head

2

being conventionally connected by conduit 4 to an oil and gas separator device indicated at 6. As is well known in the art, product from the well is frequently composed of intermixed liquid and gas and it is the function of the separator 6 to separate the gas from the oil whereby the gas may be carried through conduit 8 to some storage container or the like, while the liquid may be carried through conduit 10 to further processing. Conduit 10 may then carry the liquid to an emulsion treater 12 whereat the well product is further processed to separate usable oil from water and emulsion that may be intimately associated therewith. Additionally, a further separation of entrained gas may here occur and it again may be carried off to storage through a conduit 14. The separated water may be carried to waste via the conduit 16. The crude oil, having been separated from undesirable matter, is now in appropriate condition for measuring.

Another conduit 18 may be connected to the outlet of the treater 12, said conduit 18 carrying substantially pure crude oil to a battery of measuring tanks 20, 20. It is in these tanks 20 that the quantity production of the given well is determined. A novel feature of the invention disclosed relates to the adaptation of a plurality of floating roof-type tanks to the measuring of the crude passing from the well. In the usual instance these tanks 20 preferably have diameters of 25 feet or less. Certain important advantages appear in the use of this type of equipment in that substantial elimination of vapor space in the tanks virtually eliminates vapor loss during the frequent filling and emptying thereof. Further, the elimination of the vapor space tends to eliminate the destructive effects of corrosion on tanks themselves. After passage from the measuring tanks 20, the crude may be carried via conduit 22 to a pipe line (not shown) and from thence to storage.

It will be noted that each tank 20 in the battery comprises an outer shell 24 and a roof 26 arranged to float therein and raise and lower with the changing level 40 of the product in the tank. For illustrative purposes the left hand tank in FIGURE 1 is shown completely full, the central tank in the process of filling, and the right hand tank empty. It will also be understood while FIGURE 1 shows a battery of three tanks and FIGURE 45 2 a battery of two tanks, any number of tanks may be employed in the invention depending upon the requirements of the particular application.

Directing attention to FIGURE 2, which illustrates somewhat more in detail the structure arrangement of the tanks 20, it will be seen that each shell 24 is provided with a coned bottom 28, said coned bottom having a sump 30 located centrally therein. A plurality of roof supports 32, 32 are appropriately arranged around and secured to the bottom 28 to support the roof 26 at a determined distance from the bottom 28 when the tank is empty. The roof 26 may be of any type, but is preferably cone shaped having a peripheral wall 34 secured to a dished bottom 36. Centrally of the bottom 36 an outlet 38 may be provided which is operatively connected to a hose drain 40 to drain foreign matter such as water and the like from the roof and avoid the sinking of the roof in the product. The hose drain 40 is a flexible tube which extends downwardly in the shell 24 to a point adjacent the bottom of the shell, whereat 60 it may be sealingly passed through the shell (in a conventional manner) to a drain (not shown). Water and the like on the roof 26 will drain by gravity through the hose 40 to disposal. The sump 30 is arranged to collect foreign matter in the crude and an outlet pipe 42 is provided to periodically drain said foreign matter from each tank 20. Of course, the outlet pipe 42 may

be conventionally connected to a pump or the like to accomplish draining of foreign material from the sump 30. Guide rods 44 may be positioned in each tank and secured to the bottom thereof to cooperate with the fill pipes, hereinafter described, to prevent unwanted rotation of the roof in the tank. If desired, each roof may be additionally provided with a hatch to accommodate inspection of the tank area under the roof.

Directing attention to FIGURE 4, it will be seen that the arrangement of a guide rod 44 is here illustrated. The rod 44 extends upwardly to almost the top edge of the tank and it is received within an aperture 52 formed in the roof 26 by means of a pipe and fitting connection 54. Thus it will be understood that as the roof rises and lowers, the pipe 44 is telescoped through the aperture 52.

Referring to FIGURE 4A, it will be noted that it illustrates the connection of the lower end of the fill pipe 66 to the bottom of the tank shell. The plate 50 is provided to offer a horizontal support for the arrangement. The supporting arrangement 67 comprises a base pipe 69 having a wide aperture 71 formed in the side thereof. A spreader hood 73 and a half coupling 75 are secured in any convenient manner, as by welding, to the upper end of the base pipe. The coupling 75 threadably receives the lower end of the fill pipe 66, while the spreader hood 73 projects outwardly from the arrangement 67 and over the opening 71. The opening 71, of course, provides access for product into the tank, while the spreader hood 73 tends to control oil and gas splash.

The shell 24 may be provided with an angle iron 56 rigidly welded to the inner periphery thereof adjacent its upper end. The angle 56 serves to stiffen the upper and open end of the tank shell 24 and aids in maintaining the shell 24 in the desired circular shape.

As is best seen in FIGURES 4 and 5, the roof 26 may have a flange 58 serving as a mounting for a fabric type rim sealed gasket 60. It will be particularly noted that the seal gasket 60 is preferably, in cross-section, a looped fabric which peripherally extends outwardly from the rim 34 to flexibly engage the inner surface of the shell 24. Thus the area of the tank 20 between the periphery of the roof 26 and the inner surface of the shell 24 is sealed, which tends to reduce vapor loss in this very small peripheral space to a minimum. In the preferred embodiment the seal gasket 60, though flexible, is relatively stiff which aids in maintaining the roof centrally located in the shell 24. Additionally, the seal gasket 60, at the upper portion of the roof, underlies the angle 56 which tends to prevent rain water and the like from entering the product through the rim space by channelling same centrally of the roof whereat it may be drained off through the hose drain 40 as previously noted. In the event a certain amount of rain water or other foreign material does succeed in entering the tank proper, it will be carried to the sump 30 whereat it may be removed without substantially affecting the purity of the product measured in the tank.

Attention is now directed to FIGURES 2 and 5 for purposes of illustrating the novel piping arrangement here employed. It will be seen that each tank 24 is provided with a valve support bracket 62 preferably mounted on its upper edge. The bracket 62 may be arranged to extend inwardly of the tank and carry a tank switching valve 64, said valve being disposed in the fill line 18 previously noted. A bottom port of valve 64 communicates with a fill line 66 which, as seen in FIGURE 2, is arranged to extend downwardly in the related tank 20 to a point adjacent the bottom whereat it is provided with a port 68. A further conduit 70 communicates with another port of the valve 64 and is further connected to a second valve 64 on the adjacent tank 20.

The roof 26 may be provided with a housing 72 which defines an aperture telescopically receiving the fill line 66. The housing 72 has a tripping finger 74 mounted thereon which extends upwardly toward the valve 64. A trip arm 76 is provided at the base of the valve 64 and is located in such a manner that the trip finger 74 will engage same as the roof moves upwardly during the tank filling operation. Upon engagement of the finger 74 and the arm 76 and further upon a determined movement of the arm 76 during upward movement of the roof, the valve 64 is caused to switch, which diverts incoming crude from the related fill line 66 to the conduit 70 whereat it is carried to the next tank in the battery. Considering FIGURES 2 and 3, it will be seen that the right hand tank in the battery has one port of its valve 64 connected to a feed back conduit 80 which in turn communicates with the fill line 66 of the left hand tank at a point below its association with the valve 64.

The operation of the two battery tank arrangement of FIGURES 2 and 3 will first be considered. Assuming that the left hand tank in the battery herein indicated is empty, it will be seen that the crude is carried through conduit 18 and into switch valve 64 which in its normal position will divert the crude downwardly into the associated fill line 66. At this time the roof, of course, is at the maximum bottom position and resting upon the roof supports 32. Continued crude influx will cause the associated roof to raise in the tank until said roof approaches a predetermined maximum filled condition whereat the roof mounted finger 74 engages the trip arm 76 causing the related valve 64 to switch and divert incoming crude through conduit 70 to the valve 64 associated with the right hand tank in the battery. The arm 76 of the right hand valve 64 is of course set downwardly and the incoming crude may be diverted into the associated tank through the related fill line 66. During the elapsing time while the right hand tank is filling the operator, upon visually observing that the left hand tank is filled to capacity, may note same and proceed to drain the left hand tank to the pipe line via the conduit 22 by manually opening an associated valve therein. Thus the left hand tank is draining while the right hand tank is filling and in normal operation should be completely drained before the right hand tank is completely filled. Upon complete draining of the left hand tank the valve to line 22 may be closed and the left hand tank is again ready for service. As the right hand tank is filled, the finger 74 mounted on the roof therein engages the associated trip arm 76 causing the related valve 64 to divert incoming crude through the conduit 80 which returns same to fill line 66 of the left hand tank. Upon observing this condition the operator will then manually reset the trip arm 76 to the left hand valve 64 which causes the incoming crude to be directly diverted into the related line 66 by the left hand valve 64. At this time the trip arm 76 of the right hand valve 64 may be again manually reset and the sequence described above repeated.

Referring again to FIGURE 1 which illustrates a more desirable arrangement in that three tanks are here employed, which increases the time lapse between the manual reset operations of the several tanks making it easier for the operator to accurately control the tanks. In this instance upon filling of the left hand tank, the incoming crude is diverted to the center tank and, upon filling of the center tank the incoming crude is then diverted to the right hand tank. While the center or right hand tanks are undergoing the filling operation, the operator may at his convenience drain the left hand tank in order that it may be ready to receive incoming crude which is diverted thereto through return line 80 upon filling of the right hand tank as above described.

It will be understood that the linear distance of movement of each roof 26 from its maximum downward position resting on the supports 32 to the point whereat the related finger 74 actuates the trip arm 76 may be ac-

curately determined. This fact together with a knowledge of the exact volume of the tank and a proper location of the drain points connected with the conduit 22 will accurately determine or measure the total volume of the crude put through the respective tanks 24 by simply noting the number of times each one is filled and emptied.

The accurate measurements set out above when coupled with the reduction of vapor loss as heretofore described, the prevention of corrosive effects of vapors on the equipment and the semi-automatic feature relating to tank switching substantially improves the operation of this type of equipment as compared to those heretofore used in the art.

It will be understood that the invention as disclosed is by way of illustration and not limitation and may be subject to many minor variations without departing from the spirit thereof or the scope of the appended claims.

What is claimed is:

1. In a battery of measuring tanks for use in an oil well production system, first and second tank shells having open upper ends, first and second movable roofs in said first and second shells, respectively, arranged to float on and move vertically with the surfaces of product in the shells, said roofs including means engaging the inner peripheries of the tank shells to provide vapor seals, first conduit means in communication with a product supply, a first fill line in communication with said first shell and in communication with said first conduit means, a first valve located in said first conduit means, a second fill line in communication with said second tank shell, a second valve in communication with said second fill line, a second conduit means communicating between said first valve and said second valve, a return conduit means establishing communication between said second valve and said first mentioned fill line, said valves being normally arranged to direct product flow to each related fill line, means mounted on said first roof and arranged to operatively engage the first valve to halt the flow of product into the first fill line and the first shell when the first roof is in a predetermined position and to direct product flow to the second conduit means and to the second tank shell, and means mounted on said second roof and arranged to operatively engage the second valve to halt the flow of product into the second fill line and the second shell when the second roof is in a predetermined position and to direct product flow to the return conduit means and to the first tank shell.

2. The battery of measuring tanks of claim 1 wherein there is additionally provided means to drain oil from each of the tank shells.

3. A battery of measuring tanks according to claim 1, wherein said valves are located at the top of the related shells and said fill lines extend downwardly from the

related valves and to the associated tanks, and means defined in each roof for accommodating its associated fill line and permitting relative movement between each roof and its associated fill line.

5 4. In a floating roof measuring tank for use in an oil well production system, a tank shell having an open top, drain means located in the bottom of the shell and extending outboard of the shell, a floating roof disposed within and arranged to move vertically in the shell in response to a change in the level of product in the tank shell, said roof including means engaging the inner periphery of the tank shell to provide a vapor seal, a fill line extending into the shell, a valve in the fill line externally of the shell operative to selectively close said line, roof supports in the shell and operative to limit downward movement of the roof, and means operatively connecting the roof to the valve when the roof is in a predetermined position to close the fill line and prevent entrance of oil into the tank.
